PRESSING IRON

Harold B. Reynolds, St. Albans, W. Va.

Application July 3, 1950, Serial No. 171,951

7 Claims. (Cl. 38—93)

1

The following specification relates to an improvement in pressing irons. When laundry is pressed by a hand iron, the problem is frequently presented of pressing around and under the edge of a button or similar projection. While it has been suggested to cut special recesses or grooves in the edge of the iron, or to provide slots for receiving the button, such construction tends to be difficult to handle, injurious to the goods and in the case of the slot materially reduces the effective pressing surface.

In accordance with my invention it is possible to preserve the entire pressing surface. It is also possible to provide temporarily a recess completely surrounded by a heating surface in which the button may be received while the surface of the cloth is ironed.

One of the objects of my invention is to provide a pressing iron having the usual heating surface and an interiorly disposed covered recess in which the button may be held.

A further object of my invention is to provide means by which the recess can be opened to receive the button.

Another object of my invention is to provide mechanical means convenient to the thumb of the operator to provide a recess at the moment when the button is to be received.

Other incidental objects of my invention will be evident from the following description and the accompanying drawings of the preferred form of my invention.

In the drawings:

Fig. 1 is a side elevation partially in vertical section showing a pressing iron equipped with the novel button receiver and

Fig. 2 is a fragmentary bottom view showing the pressing surface of the iron adapted to receive the button.

In brief, the invention consists in providing a circular opening in the face or pressing surface of the iron and providing a closure for this opening and means for maintaining the closure in closed position, except when mechanically retracted by manual effort.

The invention is shown as applied to a pressing iron 3. This iron has a shoe 4 of customary form providing a pressing surface.

Above the shoe, there is provided a horizontal plate 5 separated by a slight space from the shoe 4. This space may be occupied by an electric heating element not shown, and which is not a part of the invention.

The plate 5 has a slide bearing block 6, permanently attached by rivets or the like 7.

2

The block 6 has a chamber 8 extending upwardly from the bottom of the block and in line with a hole 9 in the plate 5.

The upper end of the block 6 has a slide bearing 10. Opposite the hole 9, the shoe 4 has a circular opening 11. This opening has its sides upwardly flaring, as shown in Fig. 1.

The opening 11 is adapted to receive a closure member 12. This is in the form of a disk having side edges of the same tapering slope as the inner wall of the opening 11. The disk 12 will thus form a closure which conforms to the pressing surface of the shoe 4 and by reason of the extended edge contact of the two, the disk 12 forms a portion of the heating surface.

A stem 13 rises centrally from the disk 12 and passes upwardly from the slide bearing 10. A coil spring 14 loosely around the stem 13 rests on the inner face of the disk 12 and at the opposite end 20 abuts the inner end of the chamber 8. In this manner the spring serves to hold the disk resiliently in place in closed position.

The pressing iron has the usual cover plate 15. This plate has an opening 16 through which the stem 13 extends. The handle bracket 17 rises from the cover plate 15 and is also perforated as at 18 to permit free sliding movement of the stem 13.

To assist in causing the stem and disk to rise against the pressure of the coil spring, the handle bracket 17 has an opening 19 opposite the upper end of the stem 13.

This opening 19 is a loose bearing for the fulcrum of a lever 20. The lever 20 is pivoted to the upper end of the stem 13 and extends forwardly through the opening 19.

A bracket 21 on the front of the handle bracket 17 forms the bearing of a plunger 22. The upper end of the plunger has a pad 23 for engagement for the thumb or finger of the operator.

The plunger 22 is bent forwardly and generally parallel to the handle bracket 17. The lower end of the plunger 22 is pivoted to the front end of the lever 20.

The plunger 22 is notched as at 24. When the plunger is depressed, this notch is opposite the opening of the bracket 21 and may be pushed forward to latch with the bracket.

When the plunger is depressed, it takes the position shown in the dotted lines of Fig. 1 and the lever 20 is rocked with its rear end elevated. This causes the spring 14 to be compressed and the disk 12 to be lifted into the dotted lines shown. The circular opening 11 is then open to receive the button and the pressing operation can be carried

out in all directions around the button and inwardly toward the central thread or other means by which the button is attached.

It will also be apparent that by merely pressing the pad 12 over the button and pressing down on the iron, the coil spring will be compressed so that the pressing operation can be carried out as above described.

I have illustrated and described above the preferred form of my invention without however limiting its scope beyond that of the appended claims, due latitude being given for changes in proportions, materials and minor structural details.

What I claim is:

1. In a pressing iron having a handle and a bottom shoe with a recess in the bottom surface of the shoe, a movable closure member for the recess having a stem and manually operated linkage carried by the handle and connected to the stem of the closure member and retracting the closure member above the bottom surface of the shoe.

2. In a pressing iron having a handle and a bottom shoe with a recess in the bottom surface of the shoe, a movable closure member for the recess having a stem, a spring on the stem for holding the closure member in the recess and manually operated linkage carried by the handle and connected to the stem of the closure member and retracting it above the bottom surface of the shoe.

3. In a pressing iron having a handle, a bottom shoe with a recess in the bottom surface of the shoe and an apertured plate above the shoe, a slide bearing on the plate opposite the recess, a closure member for the recess having a stem mounted in the bearing and passing through the aperture of the plate, a compression spring on the stem between the bearing and the closure member, and manually operated linkage carried by the handle and connected to the stem of the closure member for retracting the latter above the bottom surface of the shoe.

4. In a pressing iron having a handle, a bottom shoe with a recess in the bottom surface of the shoe and an apertured plate above the shoe, a slide bearing on the plate opposite the recess, a closure member for the recess, a stem for the closure member mounted in the bearing, a compression spring on the stem between the bearing

and the closure member, and manually operated linkage carried by the handle and connected to the stem of the closure member for retracting the latter above the surface of the shoe.

5. In a pressing iron having a handle and a bottom shoe with a circular recess in the bottom surface of the shoe, said recess having an upwardly diverging side wall, a movable closure member for the recess with a correspondingly inclined side wall and having a stem, and manually operated linkage carried by the handle and connected to the stem of the closure member for retracting the latter above the bottom surface of the shoe.

6. In a pressing iron having a handle, a vertical bearing and a bottom shoe with a recess in the bottom surface of the shoe, a closure member for the recess, a closure stem in the vertical bearing, spring means between the bearing and the closure member for holding the latter in the recess, 20 a lever pivoted on the handle and connected to the stem and a plunger on the handle pivoted to the lever and lifting the closure from its seat in the recess.

7. In a pressing iron having a handle, a vertical bearing and a bottom shoe with a recess in the bottom surface of the shoe, a closure member for the recess, a closure stem in the vertical bearing, spring means between the bearing and the closure member for holding the latter in the recess, a lever pivoted on the handle and connected to the stem, a plunger on the handle pivoted to the lever for tilting the latter and raising the closure member and a detent on the plunger to latch said plunger in depressed position.

35 HAROLD B. REYNOLDS.
